REFRIGERATING APPARATUS

John A. MacLean, Hampton, N. J., assignor to
 Ingersoll-Rand Company, Jersey City, N. J.,
 a corporation of New Jersey

Application August 15, 1935, Serial No. 36,372

3 Claims. (Cl. 62—152)

My invention relates to refrigerating apparatus, and particularly to regulating means therefor.

The invention is particularly adapted to a refrigerating construction wherein a liquid refrigerant is cooled by conversion of part into vapor, which is taken away and afterwards condensed. In systems of this kind the temperature of the refrigerant when cooled varies according to the load or the extent of the demand for refrigerating effect; and if the load becomes too light and the same mass of vapor continues to be removed, the bulk of the refrigerant, which remains liquid, may be cooled to such an extent as to freeze and thus stop the entire operation. To carry off the vapor that is formed an evacuator is employed, and when this evacuator has the form of a steam ejector, it must be turned on full to work efficiently and its capacity to displace vapor does not diminish when the load drops. Therefore the danger of the system freezing when the load decreases is always present.

It is an object of this invention to guard against freezing of the liquid by reducing the amount of vapor that is removed when the load falls, and in the preferred form the cooled refrigerant is maintained at or above a virtually constant minimum temperature. The end in view can be gained by means of a suitable controlling or throttling element which reduces the flow of vapor from the chamber in which the cooling takes place as the temperature of the chilled refrigerant goes down, and has the opposite effect when the temperature rises, so that more vapor can then be carried off.

Other objects and advantages of the invention are set forth in the ensuing description and the characteristic features of the invention are pointed out in the appended claims. I of course reserve the right to make changes in the embodiment described without departing from the principle of the invention or exceeding its spirit and scope.

The drawing shows in outline, mostly in section, a refrigerating apparatus having regulating means according to my invention.

The numeral 1 indicates a closed vessel called an evaporator in which liquid refrigerant, such as water, is cooled and then discharged through an outlet conduit 2. Within the evaporator some of the liquid is converted into vapor which is extracted through an outlet port 3 at the top by means of an evacuator 4 which is herein illustrated as being of the steam-ejector type. This evacuator is connected by a discharge flue 5 to a condenser 6 in which the steam and vapor are

again liquefied. The evacuator comprises a plurality of steam nozzles 7 connected to receive steam from a steam chest 8 supplied through a pipe 9. The liquid refrigerant to be cooled enters by way of a pipe 10 connected to a reservoir compartment 11 at the bottom of the evaporator. This chamber communicating with a well or space 12 is formed by a weir 13 and the adjacent portion of the wall of the evaporator. This weir rises to a considerable height above the bottom and in practice the liquid refrigerant to be cooled flows over the upper edge of this weir or through an opening 14.

In practice the steam ejector creates and maintains a vacuum in the evaporator 1, thus making it possible for the liquid to rise in the space or chamber 12 and be discharged in finely divided form at the top of the weir 13 toward the bottom. The vapor which is formed is drawn out through the opening 3 and the bulk of the refrigerant which remains liquid collects above the partition 15 and the compartment 11 and then flows into a central outlet recess 16 which is connected to the discharge pipe 2.

To restrict the removal of vapor when the load drops I mount a throttle element 17 in the outlet 3, this element being in the form of a damper mounted on a shaft 18 which also carries a pinion 19. This pinion meshes with a segment gear 20 on the shaft 21 in the evaporator 1. The segment 20 is pinned to a rod 22 made fast to an expandible casing or sylphon 23. The end of the sylphon bearing the rod 22 is movable but the opposite end is fixed and is secured to a support 24 inside the evaporator and this end communicates through a piece of tubing 25 with a thermostatic bulb 26 in the outlet space 16. Both the bulb and tube contain a fluid medium responsive to changes in temperature. These parts are so arranged that as long as the refrigerating apparatus is operating at full load the throttle 17 will be in the position indicated permitting the maximum amount of vapor to be carried off to the condenser 6. When the load falls off and refrigerant at lower temperature enters by way of the pipe 10 the temperature of the chilled refrigerant passing out through the pipe 2 decreases. When this occurs the medium in the thermostatic element 26 and tube 25 enables the sylphon 23 to contract and then the valve 17 moves to throttle the outlet 3 and cut down the amount of vapor that is evacuated.

Thus the refrigerant entering the evaporator 1 is prevented from being cooled too much. The danger of freezing is entirely obviated and the temperature of the refrigerant passing through

the outlet conduit 2 is limited and can not be decreased below a predetermined figure.

The invention is quite well adapted to serve its intended purpose and is very simple in design and 5 certain in operation.

I claim:

- 10 1. A refrigerating apparatus comprising an evaporator having an outlet in its upper part, means defining an inlet compartment at the bottom and defining an outlet recess surrounded by said compartment, and a weir forming a chamber connected to said compartment and extending above same, said chamber being open at the top to discharge into said evaporator.
- 15 2. In a refrigerating apparatus, a container having an evaporation chamber therein and an

outlet for vapor from the chamber, and partition means within the container cooperating therewith to form a reservoir in the container to which refrigerant is supplied, and means defining a refrigerant outlet recess for the chamber, said 5 partition means also forming a well through which refrigerant is conducted from the reservoir to the evaporator chamber.

3. Refrigerating apparatus comprising an evaporator tank having an evaporation compartment therein, a reservoir in the tank, means defining an outlet recess for the tank passing through the reservoir, and means in the tank for delivering the contents of the reservoir to the evaporation compartment. 10 15
